DESIGN FOR A BLOUSE

Arthur M. Lowenthal, Rochester, N. Y., assignor to Max Lowenthal & Sons, Rochester, N. Y., a co-partnership consisting of Arthur M. Lowenthal and Eugene M. Lowenthal

Application October 1, 1937, Serial No. 71,920

Term of patent 14 years

To all whom it may concern:

Be it known that I, Arthur M. Lowenthal, a citizen of the United States, residing at Rochester, in the county of Monroe and State of New York, have invented a new, original, and ornamental Design for a Blouse, of which the following is a specification, reference being had to the accompanying drawing, forming part thereof.

Fig. 1 is a front view and Fig. 2 is a side view of a blouse showing my new design; Fig. 3 is a front view of the blouse shown in Figs. 1 and 2, with the lapels folded in overlapping relation; Fig. 4 is a rear view of the blouse shown in Figs. 1, 2 and 3.

I claim:

The ornamental design for a blouse as shown.
